(57) **CLAIM**

An ornamental design for a filter mount for a portable fan, as shown and described.

DESCRIPTION

FIG. 1 is a back perspective view of a first embodiment of a filter mount for a portable fan, in accordance with the present invention;

FIG. 2 is a front perspective view of a first embodiment of a filter mount for a portable fan, in accordance with the present invention;

FIG. 3 is a back view of the first embodiment of a filter mount for a portable fan of FIGS. 1-2;

FIG. 4 is a front view of the first embodiment of a filter mount for a portable fan of FIGS. 1-3;

FIG. 5 is a right side view of the first embodiment of a filter mount for a portable fan of FIGS. 1-4;

FIG. 6 is a left side view of the first embodiment of a filter mount for a portable fan of FIGS. 1-5;

FIG. 7 is a top view of the first embodiment of a filter mount for a portable fan of FIGS. 1-6;

FIG. 8 is a bottom view of the first embodiment of a filter mount for a portable fan of FIGS. 1-7;

FIG. 9 is a back perspective view of a second embodiment of a filter mount for a portable fan, in accordance with the present invention;

FIG. 10 is a front perspective view of a second embodiment of a filter mount for a portable fan, in accordance with the present invention;

FIG. 11 is a back view of the second embodiment of a filter mount for a portable fan of FIGS. 9-10;

FIG. 12 is a front view of the second embodiment of a filter mount for a portable fan of FIGS. 9-11;

FIG. 13 is a right side view of the second embodiment of a filter mount for a portable fan of FIGS. 9-12;

FIG. 14 is a left side view of the second embodiment of a filter mount for a portable fan of FIGS. 9-13;

FIG. 15 is a top view of the second embodiment of a filter mount for a portable fan of FIGS. 9-14; and,

(Continued)

FIG. 16 is a bottom view of the second embodiment of a filter mount for a portable fan of FIGS. 9-15. In the drawings, the broken lines showing the remainder of the filter mount for a portable fan illustrate features which form no part of the claimed design.

1 Claim, 10 Drawing Sheets
